(57) **CLAIM**

The ornamental design for a car seat cover, as shown and described.

DESCRIPTION

FIG. 1 is a perspective view of the car seat cover.

FIG. 2 is a front view thereof.

FIG. 3 is a back view thereof.

FIG. 4 is a right side view thereof.

FIG. 5 is a left side view thereof.

FIG. 6 is a top view thereof.

FIG. 7 is a bottom view thereof; and,

FIG. 8 is an alternative view of the car seat cover of FIG. 1 in a position of use on a car seat.

The evenly spaced broken lines around the rear edging and around the circular seat opening depict stitching that forms no part of the claimed design. The dashed lines forming the two elongated openings in the car seat cover depict portions of the car seat cover that form no part of the claimed design. In FIG. 8, the broken lines of the car seat and the car seat buckle depict environmental subject matter that forms no part of the claimed design.
